LIGHTER

Albertus van Poppel, Driebergen, Netherlands, assignor to Venootschap onder firma Handelsonderneming
Gebr. van Poppel, Utrecht, Netherlands, a partnership of the Netherlands

Filed Feb. 27, 1961, Ser. No. 64,074

Term of patent 14 years

(Cl. D48—27)

FIG. 1

FIG. 3

FIG. 1 is a perspective view of a lighter, showing my new design.

FIG. 2 is a perspective view of the same taken at an angle of approximately 180° to the view shown in FIG. 1.

FIG. 3 is a top plan view of the same.

I claim:
The ornamental design for a lighter, as shown.
